ENGELBERT HANEMANN, OF HOLYOKE, MASSACHUSETTS.

CARBURETER

1,105,134.

Specification of Letters Patent. Patented July 28, 1914.

Application filed November 12, 1913. Serial No. 800,511.

To all whom it may concern:

Be it known that I, ENGELBERT HANEMANN, a citizen of the United States of America, residing at Holyoke, in the county 5 of Hampden and State of Massachusetts, have invented a new and useful Carbureter, of which the following is a specification:

My invention relates to improvements in carbureters for hydrocarbon or gasolene engines, and consists of certain peculiar gas- 10 and air-controlling means, which comprise a valve-provided air intake surrounding the mixing chamber and opening into the same at various points, together with a member of 15 special form for the discharge of the fuel, and other necessary and desirable features all as hereinafter set forth.

The primary object of my invention is to produce a carbureter which most thoroughly 20 and completely breaks up the gas and mixes it with the air so that a fuel mixture of the required fineness is obtained, and one which also has the proper proportions of gas and air. As a result of the improved mixture 25 which I am able to produce with this carbureter, an engine equipped with such carbureter and supplied with such mixture therefrom is more flexible and efficient, and is operated more economically because less 30 fuel is required to produce a given result.

A further object is to produce such a carbureter which is simple, compact, and comparatively inexpensive, and which entirely practicable and possessing a high degree of 35 efficiency under the various conditions incident to the use of such a device.

Other objects are to provide in a carbureter a fuel supply and an air adjustment that are automatic in action, which action is 40 simple and brought about by or results from equally simple mechanical means, and to produce a whirling motion at two points or elevations in the air supply with which my carbureter is equipped and which constitutes an important feature or features of 45 the same.

Various other objects and advantages will appear in the course of the following description.

50 I attain the objects and secure the advantages of my invention by the means illustrated in the accompanying drawings, in which—

Figure 1 is a central vertical section 55 through a carbureter which embodies a practical form of my invention; Fig. 2, a hori-

zontal section through said carbureter, taken on lines 2—2, in Fig. 1, looking down, and, Fig. 3, a top plan of the full and initial air supply members.

Similar figures refer to similar parts throughout the several views.

The carbureter casing may be constructed in any suitable manner, but as herein illustrated consists of an air tube 1 externally 60 screw-threaded at the top and bottom, a mixing chamber 3 screwed at the base on to the top of said tube, and provided above the base with an overhanging or horizontal part 4 which has an annular shoulder 5 adjacent to its outer edge, a float-chamber 6 surrounding said tube and held in place at the bottom thereon by means of a coupling nut 7 screwed onto said tube, said float-chamber being provided on one side with a 65 fuel intake projection 8, an annular channeled-forming member 9 supported on the top of said float-chamber and having a flange 10 to engage such top, and fit said shoulder 5, said member 9 being provided on one side 70 with an air-inlet chamber 11. The member 9 fits tightly around the contiguous portion of the mixing-chamber 3. There is a valve-seat 12 in the bottom of the chamber 11, and below said seat is an annular flange 13 75 which is externally screw-threaded to receive a coupling-nut 14. A flanged tubular member or elbow 15 is securely attached to the flange 13 by means of the coupling-nut 14. In practice, the elbow 15 is preferably 80 connected with the shell or casing around the exhaust of the engine, so that hot air enters said elbow and may be taken therefrom through the valve-seat 12. A flanged pipe 16 leads from the air-take member or 85 elbow 15 at the base of the tube 1, at which base said pipe is securely attached by means of the coupling nut 7. Thus it is seen that air from the elbow 15 passes to the tube 1 by way of the pipe 16, as well as to the 90 chamber 11 by way of the valve-seat 12.

Traversing the tube 1 transversely is a member 17 in which is a passage 18 that opens through opposite sides of said tube into the float-chamber 6 near the bottom 95 thereof. Rising from the member 17, in the axial center of the tube 1, is an upright nozzle 19 in which is a vertical passage 20 that opens at the base into the passage 18 and terminates at the top in a seat 21 for a 100 valve 22. It is now clear that fuel from the float-chamber 6 can be drawn therefrom

by suction through the passages 18 and 20 and the valve-seat 21, assuming, of course, that the latter be not closed by the valve 22.

The valve 22 is of special construction 5 as shown, being large at the top and pointed at the bottom and having concave sides. Said valve is, in fact, an inverted concave cone. The valve-seat is made to correspond to the valve 22, by having a convex conical 10 form, as shown. By giving these forms to the valve 22 and its seat, and especially by making said valve with a large head and concave sides, and locating the same so that the air discharge from the tube 1, both direct and by way of the passages 24, and the 15 liquid-fuel discharge from the passage 20 must necessarily impinge thereon, it results that the fuel elements are completely broken up and thoroughly commingled and combined by the time they enter the mixing 20 chamber 3 and as soon as they enter said chamber. By being thus merged into each other, as it were, the primary fuel elements are made ready for the auxiliary air which 25 enters the mixing chamber 3.

The nozzle 19 is enlarged at the upper end to form an annular shoulder 23, and leading inwardly and upwardly from said shoulder is a series of passages 24. The 30 passages 24 open through the valve-seat 21 and said passages are in tangential relation to an imaginary circle passing through the inner ends thereof as clearly shown in Fig. 3. While some of the air which enters the 35 tube 1 from the pipe 16 passes around the outside of the upper terminal of the nozzle 19, a portion of such air impinges against the shoulder 23 and is thereby deflected into the passages 24 which impart a whirling 40 motion and to the air thus deflected from its natural course, upon its entrance into the space between the valve-seat 21 and the valve 22, with the result that a more thorough mixing of the air with the fuel or 45 gas occurs initially than would be the case if the entire volume arose around the outside of the nozzle 19 and did not mingle with the gas until after the latter had risen out of said seat.

50 There is a vertical passage 25 ending at the top in a valve-seat 26 in the projection 8, also a valve 27 therein for said seat. A screw-cap 28 is provided for the projection 8 or the chamber therein. Said chamber 55 opens at 29 into the float-chamber 6. Pivotally mounted at 30 is a rocker-arm 31. The valve 27 is attached to the arm 31 at one terminal, and a float 32, in the float-chamber 6, is attached to said arm at the 60 other terminal. The arm 31 extends through the opening 29. These float-valve members operate in the usual and well-known manner to admit the liquid fuel to the float-chamber 6, and to maintain an adequate supply 65 of such fuel therein at all times. The

top of the float-chamber 6, or of the annular space contained within the member designated by said numeral, is formed or closed by the bottom parts of the mixing-chamber 3 and the member 9, and a vent opening 33 70 is provided in said member 6 for the purpose of relieving undue pressure in the aforesaid space.

It will be observed that the valve 22 is enlarged to such an extent at its outer end 75 as to materially constrict the entrance to the mixing-chamber 3, or the exit from the tube 1. Thus I avoid using a tube 1 of the Venturi type, and obtain the same or better effects than would be the case if a tube of 80 such type were employed. The valve 22 has a stem 34 rising therefrom and operating in a tube 35 which is tapped into and depends from the upper part of the mixing-chamber 3 so that such tube is adjustable 85 vertically in said chamber. A spring 36 encircles the valve-stem 34 between the lower end of the tube 35 and the valve 22. The valve-stem 34 extends beyond the tube 34 at the top, and is screw-threaded to receive a nut 37 on the protruding terminal. The nut 37 when it comes to rest on the head 38 of the tube 35 limits the downward movement of the valve 22. The valve-stem 34 90 has a head 39 at its outer end. A double 95 adjustment is thus provided for the valve 22, and means also for changing or regulating the tension of the spring 36. Usually the nut 37 is employed to regulate the spring 36, and the tube 35 to regulate the valve 22. 100 When the nut 37 is adjusted on the valve-stem 34, it either locates the valve 22 nearer the lower end of the tube 35 and so compresses the spring 36 to a greater extent, or moves said valve farther away from said tube and so decreases the compression of said spring, accordingly as said nut is screwed up or down on said stem. Having adjusted the 105 valve 22 relative to the tube 35, in the manner and for the purpose just explained, said tube is screwed up or down to so adjust the valve-stem 34 carried thereby as to prevent said valve from being fully seated. A 110 convenient means is thus provided for regulating the amount of minimum space between the needle-valve and its seat, and for manually lifting said valve to clear the seat from any obstruction. 115

Initially the fuel is drawn up through the valve-seat 21 and around the valve 22 120 through the space left when the nut 37 is at rest on the head 38, but as soon as the suction increases the force of the spring 36 is overcome, and said valve with its stem and said nut is elevated, thus increasing 125 the opening for the escape of the fuel and permitting more fuel or an increasing volume of fuel to escape or to be drawn or sucked upwardly around the enlarged head 130 of said valve and between it and the upper

end of the tube 1 into the mixing-chamber 3. When the force of the suction decreases the spring 36 acts to force the valve 22 downwardly, and as such force continues 5 to decrease said spring finally forces said valve into its lowest position. The spring 36 is aided by gravity, and in some cases gravity alone might be depended upon to prevent the valve 22 from rising too easily 10 and to return the same to closed position.

A butterfly valve is shown at 40, in the first view, to control the passage of the fuel mixture from the mixing-chamber 3 to the intake manifold of the engine, the latter not 15 being shown.

The part 4 and the member 9 inclose a hollow space or form an annular chamber 41, into which the intake chamber 11 opens at 42. In the side walls of the mixing-chamber 3 is a series of tangential openings 43, thus establishing communication between said chamber and the chamber 41 which latter is an air-chamber. Air, drawn from the chamber 41 through the tangential openings 20 43 into the mixing-chamber 3, is discharged or sucked into said mixing-chamber in such a manner as to impart to such air a whirling motion, as will be readily seen. Obviously 25 the whirling motion thus produced is most efficacious in breaking up, commingling, and 30 itself mixing with the fuel or vapor in the mixing-chamber.

A valve 44 is provided for the valve-seat 12 in the bottom of the chamber 11. A stem 35 45 rises from the valve 44 and operates in an adjusting-screw 46 tapped into the top of the chamber 11. A spring 47 is interposed between the inner end of the screw 46 and the top of the valve 44, and serves 40 to retain said valve on its seat, and to return it to such seat after being lifted therefrom, in the absence of a preponderance of pressure from below the valve, resulting from the withdrawal of pressure from above the 45 valve by the suction produced by the engine. The force of the spring 47, and consequently the force required to open the valve 44 against said spring, are increased or decreased by turning the screw 46 in or out. 50 There is a passage 48 in the screw 46 for the valve-stem 45, which passage is of sufficient length to accommodate said stem regardless of the amount of normal adjustment that may be given said screw.

55 From the foregoing both the construction and general operation of the carbureter will be understood, hence I need give only a brief explanation of the manner in which the carbureter operates as a whole, and this I will 60 now do. When the engine is started, both fuel from the float-chamber 6 and air from the members which supply the tube 1 are drawn upwardly into the mixing-chamber, the fuel escaping through the valve-seat 21, 65 after being thoroughly mixed with the air

which escapes through the passages 24, and being sucked into said chamber, with air that rises around the nozzle 19 above the shoulder 23, from between said tube and the enlarged part of the valve 22. The fuel mixture thus initially drawn into the mixing-chamber 3 is very efficient, owing to the action of the air which is drawn through the tangential passages 24, and to the consequent thorough commingling of the elements. As the suction increases the valve 22 is raised to admit to the tube 1 and the mixing-chamber an increased or increasing amount of liquid fuel mixed with the initial air. As the engine continues to require 70 more gas or fuel mixture, sufficient force is developed to raise the valve 44, against the resiliency of the spring 47, to open the way from the elbow 15 through the valve-seat 12 into the chamber 11. The air which is thus drawn into the chamber 11 is sucked from said chamber, through the part 42, into the chamber 41, thence, through the tangential openings 43, into the mixing-chamber where it immediately mixes in the 75 most thorough manner with the fuel already therein. The air from the chamber 41 has a whirling motion imparted thereto by the act of passing through the openings 43, as previously explained, and this insures the 80 proper amount of commingling between the several elements in the mixing-chamber. As soon as the required amount of additional air is received and the suction sufficiently decreased, the spring 47 acts to close the valve 85 12 into the chamber 11. The valve 44 opens more or less according to the force exerted by the suction within the chambers 3, 41 and 11, or in agreement 90 with such force.

For construction purposes and convenience the bottom or floor of the intake chamber 11 is removable, the same being screwed into place in the present case, as shown in Fig. 1.

Various changes in the shape, size, arrangement, and construction of some or all of the parts and members of the carbureter, as herein illustrated, may be made without departing from the spirit of my invention.

What I claim as my invention, and desire to secure by Letters Patent, is—

1. Air and fuel supply means, for a carbureter, comprising an air tube and a fuel nozzle therein, said nozzle being provided with a valve-seat and having a series of air passages opening into said seat from said tube, and an inverted concave conical valve for said seat.

2. Air and fuel supply means, for a carbureter, comprising an air tube and a fuel nozzle therein, said nozzle being provided with a valve-seat and having a series of tangential air passages opening into said seat from the outside of said nozzle, and an inverted concave conical valve for said seat.

3. Air and fuel supply means, for a car-

bureter, comprising an air tube and a fuel nozzle therein, said nozzle being provided with a valve-seat and having a series of tangential air passages opening into said seat 5 from said tube, said passages extending upwardly and inwardly, and an inverted concave conical valve for said seat.

4. Air and fuel supply means, for a carbureter, comprising an air tube and a shoulder 10 dered fuel nozzle within such tube, said nozzle being provided with a valve-seat and having a series of tangential air passages opening at one end beneath the shoulder on said nozzle and at the other end into said 15 valve-seat, and an inverted concave conical valve for said seat.

5. In a carbureter, an air tube, a mixing-chamber directly mounted on and attached to the upper terminal of said tube, said mixing-chamber having an exterior flange, a float-chamber supported from the bottom part of said tube; an annular member, comprising a bottom and sides, surrounding and fitting said mixing-chamber below said 25 flange and forming with said flange an air chamber, said annular member being mounted directly on said float-chamber and being provided with an intake chamber which opens into said air chamber, the latter in 30 turn opening into said mixing chamber, a valve-seat in said intake chamber, and a valve for such seat.

6. In a carbureter, an air tube, a mixing-chamber mounted on the upper terminal of 35 said tube, said mixing-chamber having an exterior flange, a float-chamber supported from the lower terminal of said tube, an annular member, comprising a bottom and sides, surrounding and fitting said mixing- 40 chamber below said flange and forming with said flange an air chamber, said annular member being mounted on said float-chamber and being provided with an intake chamber which opens into said air chamber, 45 the latter in turn opening into said mixing-chamber, a valve-seat in said intake chamber, a valve for such seat, a conduit leading to said intake chamber and opening into the same outside of said valve-seat, and a conduit 50 in open connection with said first-mentioned conduit and the base of said air tube.

7. The combination, in a carbureter, with a fuel-supply member, and a tubular member mounted for longitudinal adjustment 55 above said fuel supply-member, of a valve-

stem arranged to slide freely in said tubular member, a valve rigidly attached to the inner end of said stem and in operative position relative to said fuel-supply-member, and adjusting means for said valve-stem 60 relative to said tubular member.

8. The combination, in a carbureter, with a fuel-supply member, and a tubular member mounted for longitudinal adjustment above said fuel supply-member, of a valve- 65 stem arranged to slide freely in said tubular member, a valve rigidly attached to the inner end of said stem and in operative position relative to said supply-member, a spring interposed between said needle-valve and the adjacent end of said tubular member, and adjusting means for said valve-stem 70 relative to said tubular member.

9. Air and fuel supply means, for a carbureter, comprising an air tube and a fuel 75 nozzle therein, said nozzle being provided with a convex conical valve-seat and having a series of air passages opening into said seat from said tube, and an inverted concave 80 conical valve for said seat.

10. The combination, in a carbureter, of an air tube, a fuel nozzle therein of less diameter than the tube, such nozzle being provided with a convex conical valve-seat and having a fuel passage and a series of air 85 passages, the latter opening into said seat from said tube, and an inverted concave conical valve in said tube for said seat, said valve having a large head which is over said air and fuel passages and the passage in 90 said tube.

11. The combination, in a carbureter, of an air tube, a fuel nozzle therein of less diameter than the tube, such nozzle being provided with a convex conical valve-seat and 95 having a fuel passage and a series of air passages, the latter opening into said seat from said tube, an inverted concave conical valve in said tube for said seat, said valve having a large head which is over said fuel 100 and air passages and the passage in said tube, a mixing chamber above said tube, an auxiliary air chamber around said mixing chamber and opening into the same, and means to supply air to said auxiliary chamber. 105
